Willis

[11] Patent Number: Des. 389,907

[45] Date of Patent: **Jan. 27, 1998

[54] DUCT FOR A TOILET BOWL VENTILATION SYSTEM

Primary Examiner—Holly Baynham
Attorney, Agent, or Firm—Kenneth A. Roddy

[76] Inventor: Jerry E. Willis, 10918 Francoise, Houston, Tex. 77042

[57] CLAIM

[**] Term: 14 Years

The ornamental design for a duct for a toilet bowl ventilation system, as shown and described.

[21] Appl. No.: 51,509

DESCRIPTION

[22] Filed: Mar. 12, 1996

FIG. 1 is a perspective view of a duct for a toilet bowl ventilation system showing my new design from the top, one end, and one side; and,

[51] LOC (6) Cl. 23-04

FIG. 2 is a perspective view thereof showing my new design from the bottom, and end and side opposite that shown in FIG. 1.

[52] U.S. Cl. D23/393

[58] Field of Search D23/393; 4/213, 4/349; 55/357
